Primary Examiner — Ian Simmons*Assistant Examiner* — Shannon Weekley(74) *Attorney, Agent, or Firm* — Griffiths & Seaton PLLC(57) **CLAIM**

The ornamental design for a condiment container set, as shown and described.

DESCRIPTION

FIG. 1 is a front, top perspective view of a condiment container set showing a first embodiment of our new design; FIG. 2 is a front, bottom perspective view thereof; FIG. 3 is a front view thereof; the rear view being a mirror image of the front view; FIG. 4 is a right side view thereof; FIG. 5 is a left side view thereof; FIG. 6 is a top view thereof; and FIG. 7 is a bottom view thereof. FIG. 8 is a front, top perspective view of one of the condiment containers of the condiment container set of FIG. 1; FIG. 9 is a front, bottom perspective view thereof; FIG. 10 is a front view thereof; the rear view being a mirror image of the front view; FIG. 11 is a left side view thereof; FIG. 12 is the right side view thereof; FIG. 13 is a top view thereof; and FIG. 14 is a bottom view thereof. FIG. 15 is a front, top perspective view of the other one of the condiment containers of the condiment container set of FIG. 1; FIG. 16 is a front, bottom perspective view thereof; FIG. 17 is a front view thereof; the rear view being a mirror image of the front view; FIG. 18 is a left side view thereof; FIG. 19 is the right side view thereof; FIG. 20 is a top view thereof; and FIG. 21 is a bottom view thereof. The features shown in broken lines depict portions of the condiment container set that form no part of the claimed design.
